UNITED STATES PATENT OFFICE.

CALVIN G. UDELL, OF NORTH INDIANAPOLIS, INDIANA.

TOWEL-ROLLER.

SPECIFICATION forming part of Letters Patent No. 349,770, dated September 28, 1886.

Application filed November 9, 1885. Serial No. 182,380. (No model.)

To all whom it may concern:

Be it known that I, CALVIN G. UDELL, a resident of North Indianapolis, Marion county, Indiana, have made certain new and useful 5 Improvements in Towel-Rollers, a description of which is set forth in the following specification, reference being made to the accompanying drawings, in theseveral figures of which like letters indicate like parts.

10 My invention relates to the construction of towel-rollers and the brackets which form the sides and unite the top and back, and will be understood from the following description.

15 In the drawings, Figure 1 is a front view of the complete device ready for use. Fig. 2 is an end view of the same, drawn on a larger scale. Fig. 3 is a side view of the bracket as cast and before driven down upon the wood of the frame, drawn upon a scale with Fig. 2. 20 Fig. 4 is a perspective view showing the ear of the left-hand bracket, and showing the loop for the insertion or the removal of the gudgeon of the roller *r*.

25 In detail, *r* is the roller, made of wood, with gudgeons on its ends, in the usual way, which revolve in bearings in the brackets on each side. *t* is the top, made of a thin piece of wood, and *b* are similar pieces composing the back. By using two pieces for the back narrow 30 strips of stuff may be utilized. The bracket is made of malleable iron, and is provided with short spurs *s*, for driving into the wood, and points *p* on the back. It is also provided with upward projections or hangers *h*, having eyes for receiving screws or nails, which hold up 35 the frame against the wall. The left-hand bracket in Fig. 1 has also a projecting loop or ear, which, when the roller is raised, allows the gudgeon to be drawn through it and out 40 from the frame when the towel needs renewing, endless towels, of course, being used. The

bracket is made of the shape shown in Fig. 3, and when the wooden strips composing the top and back are inserted the iron-work is hammered down, forcing the spurs and points 45 into the wood, holding the parts tightly together. No nails or screws whatever are necessary.

I am aware that towel-rollers supported in frames and upon brackets are not new, and do 50 not broadly claim the same as my invention.

What I do claim, however, as my invention, and desire to secure by Letters Patent, is the following:

1. The towel-roller *r*, journaled at each end 55 in the metal brackets *br*, having openings to receive one or more boards, *b*, at the back and above to receive the top *t*, substantially as described.

2. The bracket *br*, made of malleable iron, 60 providing bearings for the journals of a removable towel-roller, having the elliptical opening above to receive the top *t* and openings in the rear to receive the strips composing the back of the frame, and provided with 65 spurs *s*, for securing the frame-strips in place when the spurs are driven in, all combined substantially as described.

3. The device for hanging towels, composed 70 of the roller *r*, journaled in the malleable-iron brackets *br*, the back strips, *b*, and the top *t*, forming the frame, resting in openings provided in such brackets, and secured by driving-spurs *s*, connected with the bracket, and the hangers *h*, integral with the top of the bracket, 75 all combined substantially as described.

In witness whereof I have hereto set my hand this 6th day of November, 1885.

CALVIN G. UDELL.
